[57] CLAIM

The ornamental design for an umbrella handle, as shown and described.

DESCRIPTION

FIG. 1 is a front elevational view of an umbrella handle showing my new design, the strap being broken away for ease of illustration;

FIG. 2 is a left side elevational view thereof, the right side being a mirror image;

FIG. 3 is a rear elevational view thereof;

FIG. 4 is a front elevational view of an umbrella handle showing a second embodiment of my new design, the rear being identical;

FIG. 5 is a side elevational view thereof, both sides being the same;

FIG. 6 is a front elevational view of an umbrella handle showing a third embodiment of my new design, the rear being identical;

FIG. 7 is a side elevational view thereof, both sides being the same;

FIG. 8 is a bottom plan view of all embodiments; and

FIG. 9 is a top plan view of all embodiments.

FIG. 1

FIG. 2

FIG. 3

FIG. 4

FIG. 5

FIG. 6

FIG. 7

FIG. 8

FIG. 9
